UNITED STATES PATENT OFFICE.

JOHN W. DARLEY, JR., OF BALTIMORE, MARYLAND, ASSIGNOR OF ONE-HALF
TO MICHAEL HOLZMAN, PHILIP HAMBURGER, AND LEON HAMBURGER,
OF BALTIMORE, MARYLAND.

REPETITION PIANO-ACTION.

SPECIFICATION forming part of Letters Patent No. 687,609, dated November 26, 1901.

Application filed February 19, 1900. Serial No. 5,748. (No model.)

To all whom it may concern:

Be it known that I, JOHN WESLEY DARLEY, Jr., a citizen of the United States, residing at Baltimore city, State of Maryland, have 5 invented certain new and useful Improvements in Repetition Piano-Actions; and I do hereby declare the following to be a full, clear, and exact description of the invention, such as will enable others skilled in the art to 10 which it appertains to make and use the same.

My invention relates to improvements in piano-actions, and especially in those actions known as "repetition" actions, which are designed to enable the operator to sound the 15 same note repeatedly in rapid succession and at the same time preserve that quality known as the "touch," which is very essential for the satisfaction of the performer.

Musicians who have played on an upright 20 piano provided with my improved action have found that they could produce the required modulations in a satisfactory manner, as the keys, although light to the fingers and playing freely, do not drop away from the fingers 25 of the player, as with actions of the construction now most commonly in use on upright pianos. I attribute this improved effect to the fact that the hammers are subject to an approximately equal retraction corresponding 30 in this regard to the hammers of the grand piano. At the same time I so arrange and proportion the parts that greater simplicity and a lighter and more sympathetic touch are obtained, coupled with greater ease of regulation and the presentation of a more hand- 35 some appearance at the front.

The present invention is especially intended to cover certain improvements upon the device described in my application concurrently 40 pending, Serial No. 719,096, filed June 2, 1899.

Reference is had to the accompanying drawings, wherein the same parts are indicated by the same characters of reference throughout the several views.

45 Figure 1 represents a side elevation of one of the keys, the several parts of the "action" connected therewith, and one of the supporting-frames, the rails being shown in cross-section. Fig. 2 is a similar view showing the 50 position of the parts when the key is depressed.

Fig. 3 is a front elevation of a portion of the action, four of the supporting-frames being shown and the keys being shown in cross-section. Fig. 4 is a rear elevation of a part of the action, showing three of the keys, the parts of the action connected therewith, and the adjacent supporting-frame. Fig. 5 is a cross-section through the rails, showing one of the frames in side elevation and showing the position of the lower part of the abstract 60 when the frames are tilted outwardly preparatory to being withdrawn from the case. Fig. 6 represents a side view of the sostenuto attachment, the rail being shown in section. Fig. 7 is an enlarged side view, partly in section, of the upper end of the abstract, showing the manner of attaching and the means for regulating the repetition-spring. Fig. 8 is a rear elevation of the same. Fig. 9 is an enlarged perspective view of the upper end 70 of the jack, showing the manner in which the cap is fitted around the top thereof. Fig. 10 is a perspective view showing the shape of the cap when placed upon the jack-top singly. Fig. 11 is a perspective view of a piece of 75 jack - molding, showing the caps secured thereto before the same is cut into jacks. Fig. 12 is a perspective view showing a cap cemented upon the top of the jack without being bent around at the ends. Fig. 13 is a 80 cross-section of the sostenuto rail, showing the spring and cloth tip in elevation. Fig. 14 is a plan of the sostenuto spring, showing the position of the cloth cap in dotted lines. Fig. 15 represents a side and edge view of 85 the hammer-spring.

a designates the base-board, upon which the several parts of the action are mounted, and *b* and *c* designate the supporting-rails, which are secured to the vertical frames *d*, which 90 frames, together with the said rails, form the frame which supports the several parts of the action above the keys.

e designates one of the keys which are pivoted upon the base-board *a*, as at *f*, and are 95 provided with the usual cushions beneath all their points of contact with the framework of the piano.

The various rails and other parts of the piano-action are faced with felt or other suit- 100

able material wherever they are likely to be struck by any of the moving parts, and all centers are bouched with cloth in the usual well-known way, the effect of the whole being to 5 prevent rattling and to deaden all sounds except of the strings which have been struck.

The abstract *g* is hung to the supporting-rail *c* by a three-arm jack-lever *h* and to the lower rail *b* by a straight lever *i*, and the said 10 abstract is provided at its lower end with a foot *j*, which is suitably padded and rests upon the head of the screw *k* in the inner end of the key-lever. The rear side of the foot *j* is extended and padded on its upper side, as at 15 *l*, to make contact with a wire *m*, which extends upward from the key and over the said end of the foot to prevent the abstract from separating from the screw *k*.

A rail *n* is secured to the lower part of the 20 frames *d* just above the rear ends of the keys *e* and is padded along its under side. The object of this rail *n* is to prevent the rear ends of the keys from being thrown too high.

The hammer-butts *o* are pivoted in the front 25 ends of the cross-pieces *p*, which are secured to the upper sides of the rail *c*, and the said hammer-butts have the stems *q* extending upwardly therefrom and carrying the hammers *r* at their upper ends. When in the normal 30 position, these stems *q* rest upon the soft-pedal rail *s*, which is secured to the frames *d* and padded to receive the said hammer-stems.

The jack-lever *h* is pivoted to the supporting-rail, as at 4, and has the arms 5 and 6 35 extending forwardly therefrom, the abstract *g* being pivoted to the arm 5. The jack 2 is pivoted at its lower end to the arm 6 of the jack-lever *h* and extends upward at an angle to the abstract, its upper end or head 7 normally resting beneath the lug *t* on the hammer-butts, as shown in Fig. 1.

A repetition-spring *8* is mounted in the abstract *g* and is connected with the jack 2 by a flexible connection 9, the tension of the said 40 spring being adjustable by means of the screw 10. This repetition-spring *8* is of uniform thickness and is shaped as shown in Fig. 8, the lower portion 11 being slightly enlarged and perforated to receive the screw 10, the head or shoulder 12 of which bears upon the rear side of the said spring. The lower 45 end of the spring *8* is reduced to enter a slot 13 in the abstract *g*, which secures the spring from lateral movement. A flexible pad 14 is interposed between the said spring and the abstract, just above a shoulder 15, against 50 which the lower portion of the spring is adapted to rest. This flexible pad is arranged to produce sufficient pressure between the spring and the head or shoulder of the screw 10 to preclude the possibility of rattling. From this construction it will be seen that by 55 tightening or loosening the screw 10 the tension of the spring *8* may be adjusted. The screw 10 is flattened at its front end, where it extends through the abstract, in order that it may be turned from the front of the action

for convenience in adjusting the spring. From the enlarged portion 11 the spring *8* is tapered toward the top, as shown in Fig. 8, 70 terminating in a hook 16, to which the flexible connection 9 is secured. The flexible connection 9 being secured at its other end to the jack 2 near its upper end, the tension of the spring *8* is imparted therethrough to 75 the said jack. Three different strengths of spring are to be used in order to approximately proportion their effects to suit the different-sized hammers. The springs are all to be made of the same thickness of material and the widths varied to obtain the different strengths. Each size of these springs in the abstracts should be used with the hammers having the corresponding size of hammer-spring 25, as hereinafter set forth. 80 85

The lower end of the jack 2 extends somewhat below its pivotal point in the arm 6 of the jack-lever *h* and is provided with a screw 17, which passes through a threaded opening in the said jack and is provided with a head 90 18, adapted to be struck by the cushion 19, secured to the jack-lever, between the two arms 5 and 6 thereof. When the head 18 is struck by the cushion 19, the jack is forced to assume the position shown in Fig. 2. This 95 operation is termed the "release." The other end of the screw 17 extends through the slot 13 in the abstract and has on its front end a square or hexagonal head 20, by means of which it can be turned from the front of the 100 instrument. The weight of the front end and head of the screw 17 is so proportioned that the jack 2 will be dynamically balanced about its pivot. The upper end of the abstract *g* is provided with a stop 21, against 105 which the jack stops and rests in its normal position, and just above the said stop 21 a wire 22 is secured to the abstract and extends rearwardly, terminating just above the lug *t* on the hammer-butts, the object of the said 110 wire being to assist the hammer in its return when the key is being struck very rapidly.

Near the upper part of the frames *d*, on the rear side thereof, are formed lugs 23, upon which is secured a rail *y*, the said rail being 115 held in place by two screws 24, which pass through each of the said frames, one above and one below the said lugs 23, whereby the said rail *y* may be adjusted to adjust the tension of the springs 25. The springs 25 are 120 formed as shown in Fig. 15, the upper ends 61 being round to enter round holes in the lower edge of the rail *y* and the lower portion being flattened gradually from the points 62 to the lower ends 63, which lower ends are 125 adapted to bear against cushioned lugs 26 on the rear upper corners of the hammer-butts *o*. These springs are flattened in such proportion that they will bend equally at every portion of their length and are for the purpose of starting the hammers quickly on their return movement. The springs are to be so proportioned that the total retraction on the 130 hammers (consisting of the retraction due to

gravity and that due to the springs) shall be slightly greater when the hammer is near the string than it is when the hammer is some distance therefrom. These springs are made of 5 three different sizes of wire, so as to approximately proportion their effects to the varying effect of gravity on the different-sized hammers.

A stem *v* extends upwardly and forwardly 10 from the upper portion of the hammer-butt *o* and has at its outer end a counter-check *w*, which is padded, as shown, adapted to engage a back check 27, also padded, on the upper end of the abstract *g* when the hammer 15 rebounds from the string while the key is pressed down, and thus hold the hammer from further movement.

The damper-levers 28 are pivoted to the rear ends of the pieces *p* upon the rail *c* and 20 carry at their upper ends the dampers 29, which are normally pressed against the strings *x* by the damper-springs 30. The lower ends of the damper-levers are bent forwardly below the rail *c*, as at 31, and spoons 32, which extend upward from the jack-levers *h*, are adapted to strike these lower ends of the damper-levers when the abstract *g* moves upwardly, and thus move the dampers 29 away from the strings *x*. The damper-levers 28 25 are set at an angle, as shown in Fig. 4, in order to allow a screw-driver to be inserted between them to turn the screws *z* should this be necessary after the dampers are in place. The spoons 32 and the wires carrying 30 the dampers 29 are also bent at an angle to bring the operating parts to the proper positions. The rod 33 is connected with the loud 35 pedal and serves to throw all of the dampers away from the strings when the loud pedal is depressed.

The sostenuto rail 34 is mounted on curved hangers 35, which have pivotal bearings in holes 37 in the lugs 64, (see Figs. 3 and 5,) which lugs are formed integrally with the 40 frames *d*. One of the said hangers is provided with a lever 36, which is connected by its extension 38 with a rod 39, which is operated by the sostenuto pedal. The sostenuto rail is formed of two pieces, the rail proper 45 being L-shaped in cross-section, as shown in Fig. 13, and the other piece 41 being square in cross-section and fitted into the inner angle of the L-shaped piece 40. A series of springs 50, shaped as shown in Fig. 14, (one for each 55 of the damper-levers with which it is desired to use the sostenuto attachment,) are secured in a horizontal position between the upper side of the piece 41 and the lower side of the piece 40, and the said springs extend backwardly beyond the rear edges of the piece 40 and are covered at their rear ends with cloth, as shown at 43.

The damper-levers having the sostenuto attachment are provided with forwardly-extending wires 44, arranged in such position 60 that their forward ends will just clear the rear ends of the cloth tips 43 of the springs

42 when the sostenuto rail 34 is in its normal position. In Fig. 6 the dotted lines show one of the dampers and the sostenuto rail in their 70 normal positions and the solid lines show the position these parts assume when the corresponding key has been depressed and the sostenuto rail has been moved rearwardly by the sostenuto pedal. The depression of the 75 key causes the damper to move forwardly and the front end of the wire 44 to move in the arc of a circle forwardly and downwardly. The sostenuto rail being then moved backwardly, the rear end of the cloth 43 of one 80 of the springs 42 will pass over the end of the wire 44 and prevent the damper from returning to its normal position when the key is released, thus allowing that particular string to continue to vibrate. The cloth 43 of the 85 other springs 42 will pass beneath the ends of the other wires 44, and when the keys corresponding therewith are depressed these wires will strike the tops of the cloth 43 of the springs 42, which will be slightly de- 90 pressed thereby and not interfere with the action of the dampers. As will be seen by reference to Fig. 13, the springs 42 are free to bend downwardly, but are prevented from bending upwardly by the rear edge of the L- 95 shaped rail 40. The backward movement of the sostenuto rail is limited by screw-stops 70, having felt or padded heads 71, and so adjusted on the frames *d* as to stop the sostenuto rail at the proper position. 100

The head 7 of the jack 2 is preferably covered with a cap 50 of hard or vulcanized fiber, which substance may be advantageously employed for this purpose for the reasons that it presents a smooth enduring surface for the 105 head of the jack, it may be easily bent to the proper shape, and may be glued or cemented securely to the head of the jack. The caps 50 may be bent to the proper form and secured to each jack separately, as shown in 110 Figs. 9, 10, and 12, or the vulcanized fiber may be secured to the top of the jack-molding 51, as shown in Fig. 11, after which the molding may be cut into jacks. The caps 115 may be formed of a bent strip cemented to the jack-top, as is shown in Fig. 12, or in addition to cementing the cap may be bent around the corners of the jack-top, as is shown in Figs. 9 and 11, the form of the cap in this instance being shown in Fig. 10. 120

The frames *d*, which support the action, are formed with feet 52, having rounded heels 53 and similar-shaped toes 54, the heels 53 resting in depressions or recesses 55 in the footpieces 57. The upper ends of the frames 125 *d* are secured to the frame of the instrument by means of the screws 58 and nuts 59. Forwardly-extending hooks 60 are formed on the upper ends of the frames *d*, against the inside surface of which near their points the 130 screws 65 of the soft-pedal rail *s* bear, and thus limit the outward movement. The rail *s* is to be operated by the soft pedal in any approved manner. When the frames *d* are

properly secured in place, they occupy the position shown in Figs. 1 and 2 and in dotted lines in Fig. 5, the heels 53 resting in the depressions 55 and the toes 54 a little above the depressions 56, the nuts 59 being screwed down upon the upper ends of the said frames to secure them in an upright position. When it is desired to remove the action, the nuts 59 are removed, and the frames are then tilted forward to the position shown in solid lines in Fig. 5. During this movement the frames turn upon the heels 53, the axis of which motion being directly beneath the point of contact of the wires *m* with the feet *j* of the abstract the said feet will move forwardly away from the said wires until when the toes 54 rest in the depressions 56 the said feet will be clear of the said wires, as shown in Fig. 5. The frames *d* may then be lifted out of the piano, bringing with them the several rails and the parts of the action carried thereby and leaving the keys and wires in place. In replacing the action the toe 54 is to be first placed in the depression 56 and the action revolved on toe 54 as a pivot until the heel 53 gets a bearing in the depression 55, when the heel 53 acts as a pivot and further motion brings the action into its correct place, the pad *l* sliding under the wire *m*. The keys may be easily removed by lifting the front ends thereof until they are clear of the pivot *f*, when they may be turned sidewise and removed, the wires *m* passing between the feet of the abstracts.

35 The operation of the invention will be clearly understood from the foregoing and further description thereof is believed to be unnecessary.

Having thus described my invention, what I claim, and desire to secure by Letters Patent of the United States, is—

40 1. In a piano-action, the combination with a sostenuto rail and dampers, of a plurality of flat springs with an indented end secured to said sostenuto rail, and a cloth tip secured over and held by said indented end to engage the damper, substantially as described.

45 2. In a piano-action, the combination with a series of frames supporting the several parts of the piano-action, and having feet with rounded heels and toes formed thereon; of footpieces secured to the instrument and having depressions to receive the said heels and toes of the frames, and means for securing the frames in an upright position; substantially as described.

50 3. In a piano-action, the combination with a series of frames supporting the several parts of the piano-action, and having feet with rounded heels and toes formed thereon; of footpieces secured to the instrument and having depressions to receive the said heels and toes of the frames, the relation of the said heels and toes and depressions being such that when the frames are in an upright position one of the toes will be slightly above the corresponding depression, allowing the

frames to be tilted forwardly, and means for securing the frames in an upright position; substantially as described.

4. In a piano-action, a spring formed of sheet metal and having a bearing on a member of the action, a screw for adjusting said spring, said screw passing through the said member and having a shoulder which forms a second bearing for the spring, substantially as described.

5. In a piano-action, the combination with a hammer - spring rail, of springs having rounded upper ends to enter holes in the said rail, said springs being gradually flattened toward their lower ends, substantially as described.

6. In a piano-action, the combination with a jack-lever, and a jack pivoted to the said lever, of an abstract also pivoted to the said jack-lever, a spring having one end enlarged and perforated, and tapering gradually toward the other end, a screw passing through the perforation in the large end of the spring and into the said abstract, a flexible connection between the small end of the spring and the said jack, and means for moving the abstract to operate the said jack; substantially as described.

7. In a piano-action, the combination with a jack-lever, and a jack pivoted to the said lever, of an abstract also pivoted to the said jack-lever, a spring having one end enlarged and perforated, and tapering gradually toward the other end, a screw passing through the perforation in the large end of the spring and through the abstract, the said screw being flattened at the end projecting through the abstract, a flexible connection between the small end of the spring and the said jack, and means for moving the abstract to operate the said jack; substantially as described.

8. In a piano-action, the combination with a jack-lever, and a jack pivoted to the said lever, of an abstract also pivoted to the said jack-lever, a spring having one end enlarged and perforated, and tapering gradually toward the other end, a hook formed onto the small end of the spring, a screw passing through the said spring and through the abstract, a flexible connection between the said hook and the jack, and means for moving the said abstract to operate the said jack; substantially as described.

9. In a piano-action, the combination with a jack-lever, and a jack pivoted to the said lever; of an abstract also pivoted to the said lever and having a slot therein, a spring having one end enlarged and perforated, and reduced below the said perforation to enter the said slot, the said spring tapering gradually toward the other end, a screw passing through the perforation in the said spring and through the abstract, a flexible connection between the small end of the said spring, and the said jack, and means for moving the said abstract to operate the said jack; substantially as described.

10. In a piano-action, the combination with damper-levers and dampers carried thereby, and wires extending forwardly therefrom; of a rail having a series of springs extending 5 rearwardly therefrom in proximity to the said wires, means for moving the dampers forwardly, and means for moving the said rail backwardly to cause the said springs to engage with the said wires; substantially as described. 75
11. In a piano-action, the combination with damper-levers and dampers carried thereby, and wires extending forwardly therefrom; of a rail formed of an inverted-L-shaped piece, 15 and a square piece placed in the angle thereof; springs held between the two said pieces and projecting rearwardly, means for moving the dampers forwardly, and means for moving the said rail backwardly to cause the said 20 springs to engage the said wires, substantially as described. 80
12. In a piano-action, the combination with damper-levers and dampers carried thereby, and wires extending forwardly therefrom; of a rail formed of an inverted-L-shaped piece, 25 springs secured beneath the rearwardly-extending portion of the said L-shaped piece and extending beyond the rear edge thereof, means for moving the dampers forwardly, 30 and means for moving the said rail backwardly to cause the said springs to engage the said wires; substantially as described. 85
13. In a piano-action, the combination with damper-levers and dampers carried thereby, 35 and wires extending forwardly therefrom; of a rail formed of an inverted-L-shaped piece, springs secured beneath the rearwardly-extending portion of the said L-shaped piece and extending beyond the rear edge thereof, caps 40 of fabric secured on the rear ends of the said springs and extending beneath the edge of the said L-shaped piece, means for moving the dampers forwardly and means for moving the said rail backwardly to cause the said 45 springs to engage the said wires; substantially as described. 90
14. In a piano-action, the combination with damper-levers and dampers carried thereby, and wires extending forwardly therefrom; of a rail formed of an inverted-L-shaped piece, 50 and a square piece placed in the angle thereof, springs formed with heads on each end, caps of fabric secured on one end of each of the said springs, the other ends of the said springs 55 being held between the L-shaped piece and the square piece, the said springs projecting beyond the rear edge of the L-shaped piece and held from upward movement thereby, means for moving the dampers forwardly, and 60 means for moving the said rail backwardly to cause the said springs to engage the said wires; substantially as described. 100
15. In a piano-action, the combination with damper-levers and dampers carried thereby, 65 and wires extending forwardly therefrom; of a rail having a series of springs extending rearwardly therefrom in proximity to the said 105 wires, brackets pivoted to the frame of the instrument, hangers secured to the said brackets and supporting the said rail, means for rocking the said hangers to cause the rail to move rearwardly, and means for moving the dampers forwardly to cause the said wires to engage the said springs; substantially as described. 110
16. In a piano-action, the combination with damper-levers and dampers carried thereby, and wires extending forwardly therefrom; of a rail having a series of springs extending rearwardly therefrom in proximity to the said 115 wires, brackets pivoted to the frame of the instrument, hangers secured to the said brackets and supporting the said rail, means for rocking the said brackets to cause the rail to move rearwardly, a stop-screw having a cushioned head to limit the rearward movement of the said rail, and means for moving the dampers forwardly to cause the said wires to engage the said springs; substantially as described. 120
17. In a piano-action, a jack-lever, a jack pivoted and driven thereby, a hammer operated by said jack, means for causing said jack to revolve with said jack-lever near the end of the stroke, and a fiber cap on the portion of the jack that contacts with the hammer-knuckle, substantially as described. 125
18. In a piano-action, the combination with a hammer-butt, and hammer carried thereby; of a jack-lever pivoted to the frame of the instrument, a jack pivoted to the said jack-lever and having a tip of vulcanized fiber to engage the said hammer-butt, a screw in the lower end of the said jack having a head to impinge against the said jack-lever near the 130 end of its upward movement, an abstract also pivoted to the jack-lever, and means for moving the said abstract to cause the said jack to impinge against the said hammer-butt; substantially as described. 135
19. In a piano-action, the combination with a hammer-butt and hammer carried thereby; of a jack-lever pivoted to the frame of the instrument, a jack pivoted to the said jack-lever, a screw in the lower end of the said 140 jack having a head to impinge against the said jack-lever near the end of its upward movement and effect the release of said jack, substantially as described. 145
20. In a piano-action, the combination with a hammer-butt, and hammer carried thereby; of a jack-lever pivoted to the frame of the instrument, a jack pivoted to the said jack-lever, a screw in the lower end of the said jack having a head to impinge against the 150 jack-lever during a part of its upward movement, the said screw extending through the said jack and through a slot in the abstract, an abstract pivoted to the said jack-lever and having a slot for the reception of the said 155 screw, and means for moving the said abstract to cause the said jack to impinge against the said hammer-butt; substantially as described. 160

21. In a piano-action, the combination with a jack-lever, and a jack pivoted to the said lever, of an abstract also pivoted to the said jack-lever, a spring having one end enlarged and perforated, and tapering gradually toward the other end, a screw passing through the perforation in the large end of the spring and into the said abstract, a flexible connection between the small end of the spring and the said jack, a stop carried by the abstract to limit the forward movement of the said jack, and means for moving the abstract to operate the said jack; substantially as described.

22. In a piano-action, the combination with a hammer-butt, a hammer carried thereby, and a lug on the said hammer-butt; of a jack-lever, a jack pivoted to the said jack-lever and having a head adapted to impinge against the said lug on the hammer-butt, a screw in the lower end of the said jack to impinge against the said jack-lever, during a part of its upward movement, an abstract also pivoted to the said jack-lever, a spring adjustably secured to the said abstract and connected with the said jack, a stop on the abstract to limit the forward movement of the said jack, a wire extending from the abstract above the lug on the said hammer-butt, and means for moving the said abstract to cause the said jack to impinge against the said hammer-butt; substantially as described.

23. In a piano-action, the combination with a hammer-butt, a hammer carried thereby, and a lug on the said hammer-butt; of a jack-lever, a jack pivoted to the said jack-lever and having a head adapted to impinge against the said lug on the hammer-butt, a tip of vulcanized fiber upon the head of the said jack, a screw in the lower end of the said jack to impinge against the said jack-lever, during a part of its upward movement, an abstract also pivoted to the said jack-lever, a spring adjustably secured to the said abstract and tapering toward its free end, a hook upon the free end of the said spring, and a flexible connection from the said hook to the said jack, a stop on the abstract to limit the forward movement of the said jack, a wire extending from the abstract above the lug on the said hammer-butt, and means for moving the said abstract to cause the said jack to impinge against the said hammer-butt; substantially as described.

24. In a piano-action, the combination with a hammer spring-rail, springs having rounded upper ends to enter holes in the said rail, and being gradually flattened toward their lower ends; of means for rocking the said rail to vary the tension of the said springs on the hammers; substantially as described.

25. In a piano-action, the combination with a hammer spring-rail, springs having rounded upper ends to enter holes in the said rail, and

being gradually flattened toward their lower ends; of means for rocking the said rail to vary the tension of the said springs on the hammers; comprising lugs attached to the action-frame and forming fulcrums for the rail, and adjusting-screws on opposite sides of the said fulcrums; substantially as described.

26. In a piano-action, the combination with hammer-butts, and hammers carried thereby; of a rail, springs having round upper ends fitted in holes in the said rail and being gradually flattened toward their lower ends to bear upon the said hammer-butts, lugs attached to the action-frame and forming fulcrums for the said rail, and adjusting-screws on opposite sides of the said fulcrums to rock the said rail and vary the tension of the said springs upon the hammer-butts; substantially as described.

27. In a piano-action, a plurality of damper-levers set at an angle to the plane in which the hammer moves, the damper-lever for each note being mounted in the flange for the corresponding hammer-butt, and means for operating the said damper-levers; substantially as described.

28. In a piano-action, a plurality of damper-levers set at an angle to the plane in which the hammer moves, the damper-lever for each note being mounted in the flange for the corresponding hammer-butt, dampers carried by the said levers, springs pressing the said dampers against the strings of the piano, and means for moving the said dampers away from the said strings; substantially as described.

29. In a piano-action, the combination with a plurality of damper-levers set at an angle to the plane in which the hammer moves, the damper-lever for each note being mounted in the flange for the corresponding hammer-butt, dampers carried by the said levers, springs pressing the said dampers against the strings of the piano, and wires extending forwardly from the said damper-levers; of means for moving the said dampers away from the said strings, and means for holding one of the said dampers away from the said strings; substantially as described.

30. In a piano-action, the combination with a jack-lever and a jack pivoted to the said lever, of an abstract also pivoted to the said jack-lever, a spring, a screw passing through said abstract and said spring, and a connection between said spring and said jack, substantially as described.

In testimony whereof I affix my signature in presence of two witnesses.

J. W. DARLEY, JR.

Witnesses:

BLANCHE SMITH,
HENRY A. HIPPLER.
